LIPSTICK HOLDER

August Mitchell, New York, N. Y., assignor to
 Scovill Manufacturing Company, Waterbury,
 Conn., a corporation of Connecticut

Application December 1, 1934, Serial No. 755,535

4 Claims. (Cl. 206—56)

This invention relates to lipstick holders and the like.

It is an object of the invention to provide an improved lipstick holder of the so-called automatic or one-handed type, that is, of the type in which the holder is opened automatically by the same movement that advances the lipstick.

With this general object in view the invention consists in the features, combination, details of construction and arrangements of parts which will first be described in connection with the accompanying drawing and then more particularly pointed out.

In the drawing:

15 Figure 1 is a perspective view of a lipstick holder constructed in accordance with the invention;

20 Figure 2 is a vertical sectional view of the same, with parts shown in elevation and broken away, the holder being closed;

Figure 3 is a vertical sectional view showing the holder open;

Figure 4 is a sectional view (enlarged) taken on the line 4—4 of Figure 3, and

25 Figures 5, 6, 7 and 8 are perspective views of certain parts removed.

Referring to the drawing, there is provided an outside casing 15 which is conveniently rectangular in cross section. For purposes of 30 assembly the lower end of the casing is open, to be closed by a separate closure later referred to. The upper end of the casing is rounded and is cut away to form a discharge opening 16.

In the casing is a liner which is conveniently 35 formed in one piece from a flat stamping. This liner comprises side walls 17, 18 having rounded upper and lower ends. Integral with the side walls is a connecting wall 19 which terminates short of the rounded ends of the side walls, as 40 appears more clearly in Figure 5.

The invention in its entirety includes a shutter for the discharge opening 16 in the form of two opposing flexible strips capacitated to meet to close the opening and to separate to open the same. While this shutter and its operating means may vary in construction, in the embodiment here shown as an example, guided between the upper rounded ends of the liner and the rounded top of the casing are two 45 shutter strips 20, 21 of suitable flexible material. These strips are respectively connected, for example by riveting, to the opposite arms 22 of a U-shaped operating bar which straddles or embraces the liner. The cross-piece 24 of the operating bar carries a headed pin 25 which

serves as an actuating thumb-piece. This pin works in a slot 26 formed in one side of casing 15, the slot being closed at its upper end and open at the lower open end of the casing. In the embodiment here shown as an example the shutter strips 20, 21 are formed of non-metallic material, such as a molded cellulose acetate compound, and the meeting end edges are reinforced by metallic binding clips 27.

Downward movement of thumb-piece 25 in its slot and the resulting downward movement of the operating bar 24 cause the shutter strips 20, 21 to be separated, thus uncovering discharge opening 16. Reverse movement of the thumb-piece causes the strips to approach each other until their reinforced edges meet (Figure 2), thus covering or closing the discharge opening. The closed end of slot 26 serves as a stop to limit upward movement of the thumb-piece to the proper position for the shutter strips to meet.

The invention in its entirety includes means for advancing and withdrawing the lipstick simultaneously with the opening and closing of the shutter. Although capable of various constructions, in that here illustrated as an example, one of the shutter strips, i. e. strip 20, is formed as the free end portion of a long flexible strip 28 which extends down around the bottom of the holder and has its other end secured, e. g. riveted, to a cup-shaped carrier 29 for the cosmetic pencil or lipstick 30.

The actuating strip is guided in its movements between the casing and the liner, a supplemental arcuate guide member 31 cooperating with the lower rounded ends of the liner side walls to define a curved path at the bottom of the holder.

In closed position of the holder (Figure 2), carrier 29 is withdrawn and shutters 20, 21 cover or close the discharge opening. To operate the holder, thumb-piece 25 is moved down the slot, thus moving operating bar 24. This separates and pulls down shutter strips 20, 21 to uncover opening 16 as before described. At the same time the movement of bar 24 causes actuating strip 28 to advance and move lipstick carrier 29 upwardly. By the time the end of the lipstick has reached the discharge opening, shutters 20, 21 have withdrawn out of the way so that upon continued movement of the actuating parts the lipstick is projected through the opening to a position for use (Figure 3). Upon reverse movement of the thumb-piece 25, actuating strip 28 pulls carrier 29 back into the holder and continued movement of the thumb-piece and oper-

ating bar causes shutter strips 28, 21 to return to closing position after the lipstick has been withdrawn.

While the lower end of the holder may be closed in any suitable manner, in the embodiment here illustrated as an example the closure comprises a U-shaped insert having a bottom plate 32 and side plates 33, the latter fitting into the open end of the casing with an easy fit. As 10 here shown as an example, each of the side plates 33 of the end closure has a hole 34 adapted to take over dowels 35 on the side plates 15 17, 18 of the liner. These dowels may conveniently be formed by striking up the metal of 20 the liner plates. The connection described provides simple and effective means for attaining and maintaining the proper relative position of 25 the liner in the casing.

In order to anchor the unit comprising the 20 liner and end closure in the casing, the casing 15 has a struck-in nib (not shown) which snaps into a corresponding hole 36 formed in the side plate 33 of the end closure. Each side plate is preferably supplied with such a hole so that the 25 end closure may be assembled indifferently faced.

In the embodiment of the invention here illustrated as an example, the lower end of the holder has an ornamental false cap comprising a bottom plate 37 and four roughly triangular spring 30 fingers 38 which grip the four sides of the casing.

The holder may conveniently be assembled substantially as follows: The flexible strips having been previously riveted to the operating bar 36 and the lipstick carrier, the carrier, strips and operating bar are assembled with the liner. That unit is then inserted part way into the casing, the shank of thumb-piece 25 entering the open end of slot 26. The guide piece 31 is loosely 40 positioned in the trough of the end closure 32, 33 and the latter is connected to the liner, the side plates 33 yielding sufficiently to permit dowels 35 to snap into holes 34. The complete unit is pushed home and is anchored in place 45 by the nib taking into hole 36. Finally, ornamental cap 37, 38 is pressed into place.

It will now be apparent that the various parts are secured and maintained in their proper position by the mere act of assembling the same. 50 The flexible strips are confined between the casing and the liner; the end closure is automatically anchored in place by the nib and hole 36; the liner is maintained in proper position by its automatic connection with the end closure and 55 the anchorage of the latter; guide piece 31, while loosely mounted, is confined between the liner and the bottom plate 32 and between side plates 33 and the casing; and the ornamental cap is anchored by the grip of its spring fingers 60 38.

The operation of the assembled holder has already been described.

What is claimed is:

1. In a lipstick holder and in combination, a 65 casing having an opening in its upper end, a lipstick carrier movable in the casing, whereby the lipstick may be projected through said open-

ing, a shutter for said opening comprising two oppositely disposed flexible strips capacitated to be brought together to close said opening and separated to open the same, an operating bar in the casing and connected with each of said strips, a thumb-piece located outside the casing and connected with said operating bar, the casing having a slot for said last-named connection, one of said shutter strips having a flexible extension connected at its opposite end with said carrier, whereby movement of the thumb-piece 5 displaces the shutter and the carrier.

2. In a lipstick holder, and in combination, a casing having a discharge opening for a lipstick in its upper end, a lipstick carrier movable in 15 the casing, a shutter for said opening comprising two oppositely disposed flexible strips capacitated to be brought together to close said opening and separated to open the same, an operating bar in the casing connected with each of 20 said shutter strips, an actuating thumb-piece located outside the casing and connected with said operating bar, the casing having a slot for said last-named connection, a carrier-moving element comprising a flexible strip passing 25 around the lower end of the casing and connected, respectively, with the operating bar and the carrier, and guiding means for said strips.

3. In a lipstick holder, and in combination, a casing having a discharge opening for a lipstick 30 in its upper end, a liner in the casing, a lipstick carrier slidable in the liner, a U-shaped operating bar straddling said liner, an actuating thumb-piece connected with said operating bar, the casing having a slot for said last-named 35 connection, the upper end of the slot serving as a stop to limit movement of the thumb-piece, a flexible strip connected at one end with the carrier and connected at some distance from its other end with one leg of said operating bar, 40 the free end of said strip serving as a shutter strip and being dimensioned and arranged to cover substantially half of said discharge opening when the thumb-piece is in extreme advanced position, and a complementary flexible shutter 45 strip connected with the other leg of said operating bar for covering the other half of said opening.

4. In a lipstick holder, and in combination, a 50 casing having an opening in its upper end, a lipstick carrier slidable in the casing, a U-shaped operating bar in the casing, an actuating thumb-piece connected with said operating bar, the casing having a slot for said last-named connection, a flexible strip connected at one end 55 with the carrier and connected at some distance from its other end with one leg of said operating bar, the free end of said strip serving as a shutter strip and being dimensioned and arranged to cover substantially half of said discharge opening when the thumb-piece is in extreme advanced position, and a complementary flexible shutter strip connected with the other leg 60 of said operating bar for covering the other half of said opening.

AUGUST MITCHELL.
